APPARATUS FOR REGULATING HIGH VOLTAGE

Kenneth G. Morrison, Oakland, Calif., assignor to the United States of America as represented by the United States Atomic Energy Commission

Application February 11, 1949, Serial No. 75,911

3 Claims. (Cl. 323—22)

1

This invention relates to an improved method of and apparatus for regulating high voltage. More particularly, this invention relates to a high voltage regulator wherein different parts of the regulating apparatus are maintained at different potentials and wherein a radio-frequency voltage is used to couple one part of the apparatus to the rest of the associated equipment.

Many types of regulator circuits have been developed; however, for certain types of electrical applications it is required to have a high voltage regulator which is stable over a large range of operating conditions. To achieve this condition, the present invention employs radio-frequency coupling in novel and improved combination with an amplifier to control the operation of a regulator tube in opposition to fluctuations within the load circuit.

It is therefore an object of this invention to provide an improved method and apparatus for regulating the high voltage output of a rectifier. Another object of the invention is to provide a high voltage regulator having stable operation over a large range of load conditions.

A further object of this invention is to provide a radio-frequency circuit coupled to an amplifier adapted to control the operation of a regulator tube circuit in a predetermined manner.

A still further object of this invention is to provide a voltage regulator circuit having a series-connected losser tube coupled by radio-frequency voltages to a controlling amplifier.

A still further object is to provide a high voltage regulator of the radio-frequency type wherein the modulation of the radio-frequency voltage is accomplished at a high level.

Other and further objects of this invention will be apparent to those skilled in the art to which it pertains, upon consideration of the following specification and drawings, in which:

Figure 1 shows an over-all diagram of a high voltage regulator of the radio-frequency coupled type;

Fig. 2 is a schematic wiring diagram of the control circuit and voltage standard;

Fig. 3 is a schematic wiring diagram of the high voltage regulator control panel; and

Fig. 4 is a schematic wiring diagram of the radio-frequency rectifier unit.

Referring to Fig. 1 in detail, a block diagram of a high-voltage regulator of the radio-frequency coupled type is shown. A high voltage rectifier and filter 11 of a conventional type has a positive terminal 12 connected to ground 13 by a conductor 14. A negative terminal 15 of the

2

high voltage supply 11 is connected to the cathode of a triode tube 17 (connected as a series losser tube) by a conductor 16. The anode of the triode 17 is connected to a resistance-capacitance filter comprising two resistors 18 and 19 and a condenser 21; one side of the condenser 21 is connected to ground 13. The resistor 19 of the resistance-capacitance filter unit has its remaining end connected to the output terminal 22 from which the regulated high voltage is obtainable.

A conductor 23 is connected between the output terminal 22 and a terminal 24 of a high voltage divider network 26. This network 26 comprises the series-connected resistors 27 and 28, with a condenser 29 connected in shunt with the resistor 27 to compensate the network for the higher frequencies. Two condensers 31 and 32 by-pass the conductors 33 and 34 to ground 13. These conductors 33 and 34 couple the voltage dividing network 26 to a control amplifier 36. The high voltage divider housing 37 is connected to ground 13. The conductors 33 and 34 terminate in a connector 38 which plugs into a receptacle 39 on the control amplifier 36, the chassis 25 of which is grounded by a conductor 41. This control amplifier 36 will be described in detail later.

Two terminals 42 and 43 are connected to a suitable source of alternating current for supplying the control amplifier 36 through a pair of conductors 44 and 46 and plug and receptacle 47 and for supplying power to the control box 48 through terminals 6 and 7 of terminal strip 49. A control cable 51 connects a control box 48 to the control amplifier 36 through a plug 52 and a receptacle 53. A coaxial cable 54 conveys the radio-frequency voltage from the control amplifier 36 to a rectifier unit 55. The variable rectified radio-frequency voltage obtainable at a terminal 56 of the rectifier 55 is applied to the control grid of the losser tube 17 through a conductor 57, while a chassis terminal 58 of the rectifier unit 55 is carried to the cathode of the losser tube 17 by a conductor 59.

Referring now to Fig. 2, there is shown a schematic wiring diagram of the control amplifier 36 of the high voltage regulator system depicted in Fig. 1. The control amplifier unit 36 contains as a source of radio-frequency voltage, a self-excited oscillator 65 which comprises a pentode vacuum tube 63 and a shielded tuned circuit 64 connected between the control grid and the screen grid elements of this tube. The tuned circuit 64 includes an inductance 66 and two condensers 67 and 68 both of which are connected

in shunt across the inductance 66. One end of the inductance 66 is connected directly to the screen grid of the vacuum tube 63 and the other end is connected through a blocking condenser 69 to the control grid of the vacuum tube 63. A resistor 71 is connected between the control grid of the tube 63 and a ground bus 72. A variable tap on the inductance 66 is connected through a resistor 73 to a source of regulated positive voltage obtainable at a terminal 74 of a regulated low voltage supply 76. A by-pass condenser 77 is used to provide a low impedance path to ground for any radio-frequency voltage appearing at the tap on the inductance 66. The cathode, the inner shield, and the suppressor grid of vacuum tube 63 are connected directly to the ground bus 72. The anode of the pentode tube 63 is connected through a radio-frequency choke coil 78 to a second terminal 79 of the source of regulated positive voltage 76. A radio-frequency by-pass condenser 81 is connected between ground and the "cold end" of the radio-frequency choke coil 78.

The radio-frequency voltage appearing on the anode of the pentode tube 63 is coupled by a condenser 82 to one side of a shielded tuned circuit 83 of a buffer amplifier 84. The tuned circuit 83 consists of a variable condenser 86 and a tapped inductance 87 connected in shunt. The aforementioned tap of the inductance 87 connects through a parasitic suppression resistor 88 to the control grid of a buffer amplifier tube 89. The anode of this tube 89 is connected through another parasitic suppression resistor 91 to the center conductor of a coaxial cable 54, which couples the control amplifier unit 36 to the rectifier unit 55 (to be described later). The other side of the tuned circuit 83 is connected to the cathode of the buffer amplifier tube 89 through a resistor 92 and a condenser 93 connected in shunt. This cathode is also connected to the ground bus 72 by a by-pass condenser 94. The outer conductor of the coaxial cable 54 is connected by a conductor 96 to a terminal on a current meter 97, and the remaining terminal of the current meter 97 is connected to a terminal 4 of the receptacle 53. A condenser 98 is connected between the terminals 4 and 5 of the receptacle 53; terminal 5 is further connected to a terminal 99 of an unregulated source of positive voltage 101. A condenser 102 and a resistor 103 are connected to the same terminal of the current meter as is the conductor 96. The remaining terminal of the condenser 102 and the resistor 103 are connected together and are further connected to a condenser 104 which is shunted by a resistor 105. The junction between the condensers 102 and 104 and the resistors 103 and 105 is connected through a parasitic suppression resistor 107 to the screen grid of the vacuum tube 89. The remaining terminal of the condenser 104 and the resistor 105 are connected directly to the cathode of the tube 89 which is connected through a parasitic suppression resistor 108 to the anode of a vacuum tube 109. The cathode of this vacuum tube 109 is connected to the ground bus 72 by a conductor 111. A tapped bleeder resistor 112 is connected between the unregulated voltage terminal 99 and the ground bus 72; the tap on this resistor 112 is connected through a parasitic suppression resistor 113 to the screen grid of the vacuum tube 109. The junction between the tap on the resistor 112 and the resistor 113 is bypassed to the cathode of vacuum tube 109 by a condenser 114.

Terminal 1 of the receptacle 39, which is connected externally through the plug 38 to the conductor 33, is connected internally through a shunt-connected resistor 116 and condenser 117, and further through a second resistor 118 to the control grid of an input pentode tube 119. The suppressor grid and the inner shield of the pentode tube 119 are connected directly to the cathode which is connected through a resistor 121 to the ground bus 72. The screen grid of this pentode tube 119 receives its voltage through a parasitic suppression resistor 122 from a third terminal 123 of the source of regulated positive voltage 76. The terminal 123 is by-passed to ground by a condenser 124. The junction between the cathode of the buffer amplifier tube 89 and the parasitic suppression resistor 108 is connected through a negative feedback loop comprising a condenser 126 and a resistor 127 connected in series to the cathode of the input pentode tube 119. The anode of the input pentode tube 119 receives its positive voltage, through an anode load resistor 128 and an anode current meter 129 connected in series, from the terminal 74 of the regulated voltage source 76. The anode of the input pentode tube 119 is also connected through two series-connected glow lamps 130 and 131, through a current-limiting resistor 132, and then through a parasitic suppression resistor 133 to the control grid of the vacuum tube 109. The anode of the input pentode tube 119 is also connected through a condenser 134 to the junction between two resistors 132 and 133. The junction between the resistor 132 and the glow lamp 131 is connected through a resistor 136 to a terminal 137 of a source of unregulated negative voltage 138.

Terminal 2 of the receptacle 39, which is connected externally to the conductor 34, is connected internally through a conductor 139 to the terminal number 3 of the receptacle 53; terminal 2 of the receptacle 39 is also by-passed to the ground bus 72 by a condenser 141. The ground bus 72 is connected to a terminal 4 of the receptacle 39 and also to the chassis, to which the ground terminal 40 is also connected. Terminal 1 of the receptacle 53 is likewise connected to ground bus 72. Terminal 2 of the receptacle 53 is connected through a conductor 142 to the terminal 74 of the regulated positive voltage source 76.

The unregulated positive voltage supply 101 is a conventional, full-wave rectifier unit, and comprises a transformer 143, a rectifier tube 144, and a two-section low pass filter composed of two iron core inductances 146 and 147 and two condensers 148 and 149. The output of this voltage supply is obtainable across the bleeder resistor 112.

The regulated positive voltage supply 76 is also a conventional, full-wave type of rectifier comprising a transformer 151, a full-wave rectifier tube 152, and a pi section low-pass filter comprising an iron core inductance 153 and two condensers 154 and 155. The output of this rectifier is obtainable at a terminal 157. Connected between the terminal 157 and the regulated voltage output terminal 74 is a series losser tube 158 for regulating the voltage obtainable at the terminal 74.

The losser tube 158 has its control grid directly connected to the anode of a pentode tube 159. The control grid of the pentode tube 159 is connected to the junction between two resistors 161 and 162 through a resistor 163. The resistors 161 and 162 form a voltage divider across

the output of the regulated low voltage supply 76 and apply a predetermined voltage to the control grid of the pentode tube 159. A condenser 164 is connected in shunt with the resistor 152. From the terminal 74 there is a resistor 166 connected to the screen grid of the pentode tube 159; there is also a resistor 167 connected to the cathode of this same tube from this terminal 74. A series-connected potentiometer 168 and resistor 169 are connected between the screen grid of the pentode tube 159 and the ground bus 72. The "swinger" on the potentiometer 168 is connected through a resistor 171 to the unregulated positive terminal 157. The anode of the series losser tube is connected to its screen grid by a parasitic suppression resistor 172 and also to its control grid by another resistor 173. The series-connected gaseous regulator tubes 174 and 175 are connected between the cathode of the pentode tube 159 and the ground bus 72 and form a primary voltage standard for the regulated voltage supply 76. Connected in shunt with these tubes is a by-pass condenser 177. Another by-pass condenser 178 is connected between the control grid and the cathode of pentode 159.

The positive voltages obtainable at the terminals 79 and 123 are regulated by a pair of gaseous regulator tubes 179 and 180 connected in series; the current through these two gaseous tubes is limited by a resistor 182, which is connected between the unregulated positive voltage terminal 157 and the anode of the gaseous regulator tube 179.

A filter condenser 183 is connected across the output of the regulated positive voltage supply 76; that is, from terminal 74 to the ground bus 72. The primaries of transformers 143 and 151 are connected to the terminals 1 and 2 of the plug 47; one line has a fuse 184 and an "on-off" switch 186 inserted between the terminal 1 of the plug 47 and the transformers 143 and 151. A condenser 187 is connected in shunt across the primary windings of the transformers 143 and 151, while a second condenser 188 is connected between the ground bus 72 and the terminal 2 of the plug 47.

The supply of unregulated negative voltage 138 (obtainable at the terminal 137) is provided by connecting the cathode of a diode tube 189 to the junction between one anode of the full-wave rectifier tube 152 and one side of the high voltage winding of the transformer 151. The anode of a diode tube 189 is connected to one end of a resistor 191; the other end of the resistor 191 is connected to the terminal 137. A resistor 192 and a condenser 193 are connected in shunt between the terminal 137 and the ground bus 72.

The control box 48 for the high voltage regulator is shown in Fig. 3. Terminal 1 of the terminal strip 49, which is connected externally to the ground bus 72 through terminal 1 of the receptacle 53 of the control amplifier 36 (Fig. 2), is connected by a lead 194 to one end of three series-connected potentiometers 193, 196, and 197; the other end of this potentiometer 193 is connected directly to one end of another potentiometer 196, while the other end of the potentiometer 196 is connected to the bottom of another potentiometer 197. The "swinger" and the remaining end of the potentiometer 197 are connected together by a conductor 198; this junction is further connected by a conductor 199 to the terminal 2 of the terminal strip 49. This terminal 2 is connected externally to the terminal 2 of the receptacle 53 and to terminal 74 of the

regulated low voltage supply 76 (Fig. 2). The "swinger" of the potentiometer 193 is connected by a conductor 201 to the conductor 194. The shafts of the potentiometers 193 and 197 are ganged together so that they operate as a unit. Terminal 3 of the terminal strip 49, which is connected externally to the conductor 34 through the control amplifier 36 (Fig. 1), is connected internally by a conductor 202 and a condenser 203 to the "swinger" of the potentiometer 196. Conductor 202 is also connected to the "swinger" of another potentiometer 204 and further to the "swinger" of section 206C of a three pole, double throw switch 206. A current meter 207 is connected between the terminals 4 and 5 of the terminal strip 49 and is connected externally to the terminals 4 and 5 of the receptacle 53 on the control amplifier 36 (Fig. 2) where it is inserted between the unregulated voltage terminal 99 and the current meter 97. Terminal 6 of the terminal strip 49 is connected to one end of the primary winding of a step-down transformer 208 by a conductor 209; the other end of this primary winding is connected to the "swinger" of section 206B of the switch 206. The "on" terminal of section 206B of the switch 206 is connected by a conductor 211 to terminal 7 of the terminal strip 49. These terminals 6 and 7 of the terminal strip 49 are further connected by the conductors 44 and 46 to the terminals 42 and 43 (Fig. 1). The "off" terminal of the switch section 206C, one side of the secondary winding of transformer 208, one side of the potentiometer 204, and the "swinger" of the potentiometer 196 are all connected together by a conductor 212. The other side of the secondary winding of the transformer 208 is connected to the "swinger" of switch section 206A; while the "on" terminal of this switch section 206A is connected by a conductor 213 to the other end of the potentiometer 204.

Now referring to the rectifier unit 55 as shown in Fig. 4, the center conductor of the coaxial cable 54 is connected to one end of the primary winding of a radio-frequency transformer 214; the other end of the primary winding is connected to the outer conductor of the coaxial cable 54. A variable condenser 216 is connected in shunt with the primary winding for tuning purposes. The coaxial cable 54, which is insulated from the chassis of the rectifier unit 55 by a sleeve 217, goes to the control amplifier unit 36 (Fig. 2); here also a similar sleeve 217 is used to insulate the cable from the chassis.

One side of the secondary coil of the radio-frequency transformer 214 is connected to one side of a condenser 218, one end of a resistor 219, the anode of a diode tube 221, and to a terminal 56 on an insulated bushing 223 by a conductor 224. A variable condenser 226 is connected in shunt across the secondary coil of the transformer 214 for tuning purposes. A current meter 225 is connected between the other side of the condenser 218 and the other end of the resistor 219, and a by-pass condenser 227 is connected in shunt across the current meter 225 to protect it from radio-frequency current. The other side of the secondary coil of the radio-frequency transformer 214 is connected by a conductor 228 to the anode of a second diode tube 229. The cathodes of these two diode tubes 221 and 229 are connected together by a conductor 231 and are in turn connected to a chassis ground 232 by a conductor 233; a terminal 58 is also connected to this chassis ground 232. The cathodes of

these diodes 221 and 229 are connected by a conductor 236 to the junction between the current meter 225 and the condenser 218.

The operation of this radio-frequency coupled, high-voltage regulator will now be described in detail. The radio-frequency voltage is supplied from the self-excited oscillator 65, which operates in the medium frequency range and the exact frequency of which is determined by the resonant frequency of the tuned circuit 64 connected to the vacuum tube 63. A typical operating frequency might be one in which the inductance 66 and the condensers 67 and 68 resonate at approximately 5 megacycles. The oscillator control grid bias is determined by the grid resistor 71 through which the oscillator control grid current flows; while the oscillator control grid excitation voltage is determined by the position of the cathode tap on the inductance 66.

The plate circuit of the oscillator tube 63 is 20 tuned to the fundamental frequency, as determined by the tuned circuit 64, by the tuned circuit 83 comprising the inductance 87 and the condenser 86. This tuned circuit is designed so as to reflect the proper plate load back to the plate of the oscillator tube 63. The oscillator is "shunt fed," in that it receives its plate voltage through the radio-frequency choke coil 78, and the radio-frequency voltage is applied to the tuned circuit through the coupling condenser 82, thus isolating the tuned circuit 83 from the direct current anode voltage.

The vacuum tube 89 serves as a radio-frequency buffer amplifier of the class "C" type. An amplifier of the class "C" type is used so as to 35 provide, as nearly as possible, a linear change in output with respect to a change in the modulation voltage. Since the buffer amplifier tube 89 is operated with positive grid current, the grid resistor 92, and the condenser 93 provide a source of direct current grid bias voltage. The tap on the inductance 87 is adjusted to give the proper amount of grid drive to the control grid of the buffer amplifier tube 89, when the proper plate load is connected in its plate circuit.

The buffer amplifier tube 89 is operated "off of ground" by the amount of voltage developed across the modulator tube 109; and hence the cathode of the buffer amplifier tube 89 is returned to ground, for radio-frequency voltage, by the by-pass condenser 94. The resistors 103 and 105 and the condensers 102 and 104 form a compensated voltage divider for supplying screen grid voltage to the buffer tube 89. This network allows modulation of both the plate and the screen grid of the buffer amplifier 84.

Since this regulating system is concerned with changes in the high voltage which may occur at frequencies approaching zero cycles up to approximately 400 cycles per second (the major variations being due to the 360 cycle ripple component of the high voltage rectifier unit 11 (Fig. 1), and the remaining variations due to lower frequency ripple components because of rectifier unbalance, line voltage changes, and load changes) a direct coupled two-stage amplifier composed of the vacuum tubes 119 and 109 and their associated components is provided on this chassis to furnish the major portion of the gain of the system.

To protect the vacuum tube 119 during the instances when there is no output from the high voltage rectifier unit 11 (Fig. 1) or when the output of the regulator is short circuited and a high positive voltage is applied to the input terminal

1 of the receptacle 39, the resistor 116 is used to limit the control grid current flowing in the control grid circuit. The condenser 117 which shunts the grid limiting resistor 116 reduces the 5 impedance across this resistor 116 at signal frequencies. The time constant, or the product of the capacitance of the condenser 117 in farads times the resistance of the resistor 116 in ohms, must be shorter than that of any other "resistance-capacitance" combination in the high voltage divider in order that the grid of the input tube 119 shall have applied to it the true voltage output of the voltage divider as the high voltage approaches its working value.

The plate of the input tube 119 is coupled to the control grid of the second amplifier or modulator tube 109 through two glow lamps 130 and 131, which provide a substantially constant direct current potential drop and hence place the proper negative voltage on the control grid of vacuum tube 109. This glow lamp network allows the very slow direct current variations to be passed on to the control grid of vacuum tube 109. The resistor 132 in the control grid circuit limits the grid current of the vacuum tube under certain operating conditions, while the condenser 134 reduces the impedance across the network comprising the glow lamps 130 and 131 and the resistor 132 at the higher signal frequencies. The time constant of the condenser 134, resistor 132 combination is made comparable to that of the condenser 117, resistor 116 combination for the same reasons as set forth previously.

The buffer amplifier tube 89 and the modulator tube 109 are connected in series across the output of the power supply 101. The buffer amplifier tube 89, operating as a class "C" amplifier, offers a substantially constant impedance, 40 while the impedance of the modulator tube 109 varies according to the signal voltage present at its control grid. Thus, modulation of the radio-frequency voltage is obtained by varying the current which may flow through the modulator tube 109. The current meter 97 indicates this current flow and is used to give a visual check on the performance. The current meter 237 in the control box (Fig. 3) provides a visual indication at the operating position of the current flowing in the modulator-amplifier circuit.

The regulated positive voltage obtainable at the terminal 74 is used as a voltage standard for regulating the high voltage output of the high voltage regulator. This standard voltage is held 55 substantially constant by the direct current amplifier tube 159, the low voltage standard comprising the gaseous regulator tubes 174 and 175, the series losser tube 158, and the associated components. The standard voltage obtainable 60 from the terminal 74, which is in the order of 500 volts, is maintained constant within one part in 5000 or better for periods of less than one hour. For longer periods the stabilization is one part in 2500 or better.

65 The modulated radio-frequency voltage obtainable at the anode of the buffer amplifier tube 89 is carried to the rectifier chassis (Fig. 4) by the coaxial cable 54. The actual coupling between the control amplifier chassis 36 and the rectifier unit 55 takes place in the radio-frequency coupling transformer 214. This transformer has a tuned primary and a tuned secondary, and the spacing between the two coils is such as to have a coupling coefficient greater than the critical 70 value. This coil assembly is immersed in trans-

former oil to provide the necessary insulation to withstand at least 40 kilovolts direct current with a reasonable safety factor.

The radio-frequency voltage developed across the secondary of the radio-frequency transformer 214 is rectified by a diode 229, and then the pulsating direct current is filtered by the condenser 218 plus the input capacity of the series regulator tube or tubes 17 (Fig. 1). The load resistor 219 is chosen to flatten properly the response curve of the coupling unit 55, and the current meter 225 indicates the amount of direct current voltage output to the control grid of the series regulator tube 17. The diode 221 is a protective device connected from the regulator tube 17 control grid to cathode to prevent the control grid of the losser tube 17 from going positive with respect to the cathode and thereby causing an excessive grid current to flow and perhaps ruin the vacuum tube.

Referring now to Fig. 3, the output of the voltage standard 76 obtainable at the terminal 74 (Fig. 2) is applied across the resistors 193, 196, and 197 in series to ground. The bottom end of the resistor 28 of the high voltage divider network 26 (Fig. 1) is connected through the control amplifier 36 to the terminal 3 of terminal strip 49 and then by a conductor 202, switch section 206C, and a conductor 212 to the movable contact of resistor 196. Thus it is seen that a sample of the high negative voltage is compared to a part of the positive standard voltage, the value of which is determined by the settings of the movable contacts of the resistors 193, 196, and 197. These two voltages, being of opposite sign, add algebraically to provide the proper low negative voltage to be applied to the control grid of the input tube 119 of the control amplifier (Fig. 2). The variations in value of the high negative voltage also appear on this low negative voltage which is used to control the regulator system. These variations are amplified by the vacuum tube 119, further amplified by the modulator tube 109, and are then used to modulate the radio-frequency voltage applied to the control grid of the buffer amplifier tube 89 by the self-excited oscillator tube 63. This radio-frequency voltage, which is varying in amplitude, is coupled by the radio-frequency transformer 214 to the rectifier unit 55; here the modulated radio-frequency voltage is demodulated or converted into a varying direct current voltage of such polarity that when it is applied to the control grid of the losser tube the original voltage variations are corrected. Thus when the high voltage tends to change in magnitude, a correcting voltage is applied to the control grid of the series losser tube, which corrects the original variation; and the high voltage is kept substantially constant. The resistors 193 and 197 act as the high voltage "fine" control, while the resistor 196 is the high voltage "coarse" control.

When the switch 206 is thrown to the "on" position, three operations are accomplished: the transformer 208 is energized, the resistance element of the potentiometer 204 is connected across the transformer secondary, and a portion of the resistor 204 is shunted across the condenser 203. In this manner a small alternating current voltage is inserted in series with the high negative voltage sample and modulates the signal voltage applied to the control amplifier input. This in turn modulates the high negative voltage output obtainable at the terminal 22 (Fig. 1). This modulation of the high voltage is desirable when a

beam scanner is used to monitor the beam, as for instance when this high voltage regulator is used in conjunction with a mass separator.

Although I have described my invention with respect to a particular embodiment thereof, it is not limited to this embodiment nor otherwise except by the terms of the following claims.

What is claimed is:

1. In a high-voltage regulating network of the radio-frequency coupled type wherein part of the apparatus is maintained at a low potential, the combination comprising a losser tube connected in series with a load across a source of voltage to be regulated, a resistor bank across said load for obtaining a sample of the voltage thereacross, a standard voltage source, a comparison circuit comparing the output of said standard voltage source with the voltage across said resistor bank for producing a differential voltage, a source of radio-frequency voltage, a buffer amplifier having a control electrode connected to said radio-frequency voltage source and thereby amplifying said radio-frequency voltage, a modulator tube having a control electrode and having an output connected to said buffer amplifier and modulating the amplified radio-frequency output thereof, a direct coupled amplifier having its output applied to the control electrode of said modulator, said direct coupled amplifier having control means, and means impressing upon said control means the differential voltage from said comparison circuit, whereby said differential voltage is amplified and impressed on said radio-frequency voltage by said modulator, and a rectifier unit connected between said buffer amplifier and the grid of said losser tube for demodulating said modulated radio-frequency voltage and applying the resulting varying unidirectional voltage to the control grid of said losser tube for controlling the internal impedance thereof, and counteracting variations in said load voltage.
2. In a high-voltage regulating network of the radio-frequency coupled type wherein part of the apparatus is maintained at a low potential, the combination comprising a losser tube connected in series with a load across a source of voltage to be regulated, a resistor bank across said load for obtaining a sample of the voltage thereacross, a comparison network connected to said resistor bank and including a standard voltage source and producing a differential voltage from a comparison of the resistor bank voltage and the standard voltage, a source of radio-frequency voltage, a buffer amplifier vacuum tube and a modulator vacuum tube each having at least a cathode, an anode and a control grid, said buffer amplifier tube and said modulator tube being connected in series across a source of power and said radio-frequency voltage source being connected to the control grid of said buffer amplifier, a direct coupled amplifier coupled to the control grid of said modulator tube, said direct coupled amplifier having a control grid connected to the output of said comparison network whereby a differential voltage produced by the comparison of said sample voltage and said standard voltage is amplified and applied to the control grid of the modulator tube for varying the anode current of said modulator tube, thereby varying in amplitude the radio-frequency output voltage of said buffer amplifier tube, and a rectifier unit having an input circuit connected to the anode of said buffer amplifier for demodulating said variable amplitude radio-frequency voltage, and an output circuit applying said varying unidi-

11

rectional voltage to the control grid of said losser tube for controlling the internal impedance thereof, and counteracting variations in said load voltage.

3. In a voltage regulator the combination comprising a variable electronic impedance connected between a voltage source and a load, a voltage divider connected across said load, a comparison network including a standard voltage source and means to compare the voltage across a predetermined portion of said voltage divider to said standard voltage whereby a differential voltage is produced, an amplifier tube having an anode and control electrode, means impressing said differential voltage upon the control electrode of said amplifier tube, a modulator tube having an anode and control electrode, means connecting the anode of said amplifier to the control electrode of said modulator tube, a cathode-modulated class C amplifier tube having an anode, cathode, and control electrode, means connecting the cathode of said modulated amplifier

12

to the anode of said modulator tube, a power supply connected in series with said modulator and modulated amplifier, a self-excited oscillator coupled to the control electrode of said modulated amplifier, a rectifier circuit changing the output of said modulated amplifier to a direct current voltage, and means impressing said direct current voltage upon said variable electronic impedance whereby the value of said impedance is varied to compensate for fluctuations in load voltage.

KENNETH G. MORRISON.
